INFLATABLE LIFE PRESERVER BELT

Don S. Ibsen, Bellevue, Wash.

Application August 6, 1956, Serial No. 42,506

Term of patent 14 years

(Cl. D71—1)

The figure is a plan view of an inflatable life preserver belt embodying my new design and illustrating the belt in uninflated position. The opposite side of the belt is the same as the side shown except for the circular center element.

I claim:

The ornamental design for an inflatable life preserver belt, as shown and described.
